UNITED STATES PATENT OFFICE.

MALCOLM U. WIKSTROM, OF DETROIT, MICHIGAN.

APPARATUS FOR FORMING METAL TUBES.

Application filed August 22, 1924. Serial No. 733,586.

To all whom it may concern:

Be it known that I, MALCOLM U. WIKSTROM, a citizen of the United States, and resident of Detroit, in the county of Wayne 5 and State of Michigan, have invented a new and useful Improvement in Apparatus for Forming Metal Tubes; and I do hereby declare the following to be a full, clear, and exact description thereof.

10 My invention relates to apparatus for forming tubes, and particularly to means for facilitating the handling of the plug or mandrel over which seamless tubes are rolled.

15 In my application, Serial No. 625,771, filed March 17, 1923, I have shown apparatus for utilizing a spherical plug or mandrel in forming seamless tubes. The present application constitutes an improvement in 20 the means for manipulating such spherical plug.

Heretofore the practice has been, when employing plugs or mandrels of elongated form, to withdraw them from between the 25 roll pass manually by tongs. In many cases two workmen were required to perform this service. In my application referred to above, provision is made for returning the spherical ball by a reverse movement of the 30 tube upon completion of a pass. The object of my present invention is to provide means for automatically returning the ball or plug, thereby giving it a start ahead of the returning tube, so as to give the ball 35 time to drop out of the way before the tube is returned.

One manner in which my invention may be practiced is shown in the accompanying drawing wherein Fig. 1 is a sectional elevational view showing a plug in operative position in the roll pass, and Fig. 2 is a similar view showing the manner in which the plug is returned to starting position.

40 The rolls 3 may be of a form suitable for 45 rolling tubes. A mandrel bar 4 is provided with a recessed portion which is closed by a head or seat portion 5 that has screw threaded engagement with the recessed portion of the mandrel. A compression spring 50 6 is contained within the recess of the mandrel bar 4 and seats against a collar 7 formed on a plunger 8 that extends through a longitudinal opening in the mandrel head 55 5. Instead of the spring an air pressure can be employed which could be admitted through a hole 12 in the mandrel bar 4.

A tube 9 is fed between the rolls 3, over a mandrel or plug 10 that is held in position in the roll pass by the mandrel head 5, to expand the inside of the tube 9 as it moves 60 between the rolls 3.

The plug 10 is advanced by reason of movement of the tube, from the position indicated in full lines in Fig. 2 to the position indicated in Fig. 1, thereby compressing 65 the plunger 8 against the spring 6 so that when the tube 9 has advanced to the position indicated in Fig. 2, the plug 10 will be released therefrom and the spring 6 permitted to return the plug 10 to the guide 70 trough 11, as indicated in dotted lines in Fig. 2.

Various detail changes may be made without departing from the spirit and scope of the invention as defined in the accompanying 75 claims.

I claim as my invention:

1. In apparatus for making tubing, the combination with rolls, of a mandrel bar, 80 a spherical plug engaging said bar in the pass of the rolls, and spring means stressed during advancing movement of said plug for returning said plug to a point in front of the rolls upon completion of a pass.

2. In apparatus for making seamless tubing, the combination with rolls, of a mandrel bar, a spring pressed plunger normally protruding to the front of said bar, and a spherical plug adapted to engage said plunger and bar when in the pass of the rolls. 85 90

3. In apparatus for making tubing, the combination with rolls, of a mandrel bar having a recess at its forward end, a spring within said recess, a plunger seating against said spring and normally projecting to the front of said bar, and a spherical plug adapted to depress said plunger and engage the front of the bar when in operative position in the pass of the rolls. 95

4. The combination with rolls for forming tubes, of a mandrel bar, a plug movable into the pass of the rolls, and resilient means placed under stress upon advance movement of said plug into said pass, for returning said plug to position. 100 105

In testimony whereof I, the said MALCOLM U. WIKSTROM, have hereunto set my hand.

MALCOLM U. WIKSTROM.
